UNITED STATES PATENT OFFICE.

ALFRED SCHLESINGER AND HEINRICH LEHNHOFF, OF BERLIN, GERMANY, ASSIGNEES
TO BERLINER MASCHINENBAU-ACTIENGESELLSCHAFT VORMALS L. SCHWARTZ-
KOPFF, OF BERLIN, GERMANY, A CORPORATION OF GERMANY.

INKING DEVICE FOR PRINTING PRESSES.

Application filed May 14, 1927, Serial No. 191,437, and in Germany May 17, 1926.

There are known inking devices in which a cylinder for triturating the ink preliminarily is arranged between the ink-box roller and the inking cylinder of the applying roller set. Although a considerably better trituration of the ink is obtained by that arrangement, still, the ink supply to the inking cylinder proceeds discontinuously because the member located between the cylinder for triturating the ink preliminarily and the inking cylinder contacts only alternately with one and the other cylinder.

10

The drawback stated is overcome in the present invention by the feature that the ink is taken off the cylinder for triturating it preliminarily not merely by one conveying member, but by two or more such members. These members may form rollers, or special devices may be provided, with the aid of 15 which the ink-carrying surface contacts now with the one and then with the other cylinder so that a continuous supply of the ink is obtained which could not be obtained with the known constructional forms of devices of 20 the kind in question. The path of the ink conveying member forwardly and rearwardly requires, with said constructional forms, too much time and it is not possible to supply during that time ink triturated preliminarily.

25

30 By the alternating actuation of a plurality of ink conveying members a perfect compensation is attained. The ink supply takes place uninterruptedly; this effect can be attained solely by subdividing the path in the manner stated.

35 The invention is illustrated diagrammatically and by way of example on the accompanying drawing, on which

40 Figure 1 is a side-view of an inking roller set designed according to this invention, and

45 Figure 2 is a similar representation, some of the ink-conveying members being in another position.

50 On the drawing, 1 denotes the ink-box roller and 2 a cylindrical ink conveying member, or conveying roller respectively, which conveys the ink from the roller 1 to the cylinder 3 on which the ink is thoroughly triturated preliminarily by means of the cylinders 4. The conveying roller 5 and 6 convey alternately the triturated ink from the cylinder 3 to the inking cylinder 7.

The ink conveying rollers 5 and 6 are actuated by cams 8 and 9, as well as by rolls 10 and 11 in the one direction and by springs 19 55 or the like in the other direction, however, any suitable means may be used to this purpose. The members 5 and 10, as well as 6 and 11, are carried by bell-crank levers 15, 15¹ located on pivots 16, 16¹ affixed to the 60 frame 20 of the printing press.

It is obvious that in consequence of the cams 8 and 9 having different angular positions upon their shafts 18 and 19 respectively the ink is supplied practically continuously 65 to the inking cylinder 7. In those periods of time in which the rollers 5 and 6 do not convey ink they serve as triturating rollers while co-operating with the inking cylinder 7.

The cams 8 and 9 may be actuated for instance by cog-wheels 12 and 13 which are suitably connected with said cams and mesh with an intermediate driving cog-wheel 14 that is common to them and secured to the 70 shaft of the cylinder 7.

The axes of the cylinders, rollers and cog-wheels are journalled in the frame of the machine in the usual manner.

75 We claim:

1. An inking device for printing presses 80 provided with a cylinder for triturating the ink preliminarily, comprising, in combination with said cylinder and with the inking cylinder proper, a plurality of ink-conveying members arranged between said two cylinders, swinging levers for moving said conveying members alternately into contact with the 85 said inking cylinder proper and means adapted to control said levers so as to hold at each time at least one of said members in 90 contact with said inking cylinder.

2. An inking device for printing presses 95 provided with a cylinder for triturating the ink preliminarily, comprising, in combination with said cylinder and with the inking cylinder proper, a plurality of ink-conveying members arranged between said two cylinders and cams for moving said conveying members alternately into contact with the 100 said inking cylinder proper and having different angular positions on their respective shafts so that they hold at each time at least one of said members in contact with said inking cylinder.

3. An inking device for printing presses provided with a cylinder for triturating the ink preliminarily, comprising, in combination with said cylinder and with the inking cylinder proper, a plurality of ink-conveying members arranged between said two cylinders, swinging levers for moving said conveying members alternately from one to the other

of the said two cylinders and means adapted to control said levers so as to hold at each time 10 at least one of said members in contact with said inking cylinder.

In testimony whereof we have affixed our signatures.

ALFRED SCHLESINGER.
HEINRICH LEHNHOFF.
